UNITED STATES PATENT OFFICE.

HARRISON S. GIPE, OF PALMYRA, AND GEORGE W. HENRY, OF DERRY CHURCH,
PENNSYLVANIA.

BOX-COVERING MACHINE.

1,127,879.

Specification of Letters Patent.

Patented Feb. 9, 1915.

Application filed November 9, 1914. Serial No. 871,126.

To all whom it may concern:

Be it known that we, HARRISON S. GIPE and GEORGE W. HENRY, citizens of the United States, residing at Palmyra, county 5 of Lebanon, and State of Pennsylvania, and Derry Church, county of Dauphin, and State of Pennsylvania, have invented certain new and useful Improvements in Box-Covering Machines, of which the following

10 is a specification.

Our invention relates to improvements in box covering machines, an object of the invention being to apply adhesive coated paper sheets to the bottom of the box, and 15 also to the top of the box, such machines being commonly known in the trade as toping machines.

A further object is to provide improved means for feeding a strip of paper coated 20 with adhesive, and applying the same to the boxes or covers, such strip automatically severed into sheets of proper length and pressed tightly upon the box or cover.

A further object is to provide improved 25 means for supporting the strip of paper in position to be pressed downwardly upon the box or cover, such means comprising a plurality of needles movable through oil saturated waste to keep the needles free from 30 adhesive which would otherwise accumulate thereupon, and interfere with the operation of the machine.

A further object is to provide an improved construction of adjustable support 35 for a box or cover mounted upon an improved carriage with an improved mechanism for imparting reciprocating motion to the carriage, and permitting a certain flexibility of operation to permit the perfect 40 operation of the machine.

A further object is to provide improved mechanism for controlling the application 45 of adhesive to the paper strip, and maintaining a sufficient slack in the paper from its supply roll to the adhesive roll to permit an easy operation of the machine in moving the paper.

A further object is to provide improved 50 means for positioning a strip of paper so that it will be secured between its ends to the bottom of the box under the paper sheet covering the bottom of the box.

A further object is to provide improved means for supplying the tape, holding the same in proper position, and automatically 55 severing it into proper lengths as it is supplied to the boxes on the carriage.

A further object is to so construct our improved machine as to permit the same to be adjusted to accommodate various sizes 60 of boxes and covers.

A further object is to provide a machine of the character stated which will rapidly and uniformly perform its functions and result in a saving of time and labor and 65 consequently reduce the cost of manufacture.

With these and other objects in view, the invention consists in certain novel features of construction, and combinations and arrangements of parts as will be more fully hereinafter described and pointed out in the claims.

In the accompanying drawings: Figure 1 is a view in side elevation illustrating our 75 improved machine. Fig. 2 is a similar view in side elevation of the opposite side of the machine. Fig. 3 is a top plan view. Fig. 4 is a view in vertical longitudinal section through the center of the machine taken 80 on the line 4—4 of Fig. 3. Fig. 5 is a similar view in section through the center of the machine looking in the opposite direction as indicated by the arrows 5—5, the part of the machine at the rear being shown 85 in elevation. Fig. 6 is a detail view in top plan on an enlarged scale illustrating the arrangement of needles for supporting the paper and the pressure roll with its operating means. Fig. 7 is a view in transverse 90 section on the line 7—7 of Fig. 6. Fig. 8 is an enlarged fragmentary view in section on the line 8—8 of Fig. 7. Fig. 9 is a fragmentary perspective view illustrating the box supporting carriage and its coöperating 95 parts. Fig. 10 is a fragmentary perspective view of the opposite end of the frame showing the adhesive box and its coöperating mechanism. Fig. 11 is a fragmentary view in cross section through the pressure roll illustrating its mounting. Fig. 12 is a fragmentary view in section on the line 12—12 of Fig. 11. Fig. 13 is a fragmentary view in elevation illustrating the tape holder 146

and its mounting. Fig. 14 is a view in transverse section on the line 14-14 of Fig. 13. Fig. 15 is a view in section on the line 15-15 of Fig. 14. Fig. 16 is a view 5 similar to Fig. 13 illustrating the tape guiding shuttle 137. Fig. 17 is a view in elevation illustrating the tape supplying and controlling mechanism. Fig. 18 is an 10 enlarged view partly in elevation and partly in section illustrating the tape cutting shears, and Fig. 19 is a perspective view 15 illustrating a box with the bottom sheet and tape applied thereto by our improved machine.

Fig. 1 represents a supporting frame in which a transversely positioned drive shaft 2 is mounted, and to which latter power is transmitted from any suitable source, a pulley 3 being illustrated as fixed to the drive shaft 20 and adapted to be operated by a belt (not shown).

A clutch 4 is provided on drive shaft 2, and serves to lock a sprocket wheel 5 to the shaft. This sprocket wheel 5 is connected by 25 a chain 6 with a sprocket wheel 7 on a countershaft 8 also supported in the frame 1.

The shaft 8 is provided with a pinion 9 meshing with a relatively large gear wheel 10 on a shaft 11 located in a lower plane 30 than shaft 9 and serving to operate the several features of the machine as will be hereinafter explained.

The clutch 4 is normally held in released position by means of a spring 12 to which 35 the shorter end of a lever 13 is connected. This lever 13 is pivotally connected to the frame 1 as shown at 14, and at its longer end is connected by a rod 15 with a lever 16, the latter pivotally supported between its 40 ends on the frame 1 as shown at 17.

The lever 16 is connected by a rod 18 with a foot treadle 19, so that the operator can stand at one end of the machine, and by means of the treadle 19, throw the clutch 45 into operation and start the machine, and as long as pressure is applied to the treadle, the machine will operate and as soon as released, spring 12 will automatically throw the clutch out and stop the machine.

The end of the machine, where the treadle 50 19 is located, we will term the forward end of the machine, and the opposite end, the rear end for convenience of description.

At the forward end of the machine, the 55 frame is provided with parallel guide flanges 20 to receive the grooved ends of a sliding carriage 21. This carriage 21 is made with a post 22 supporting a form 23. This form 23 is of the proper size to receive the box 60 or the cover, and it is to be understood that various sizes of forms will be supplied for the machine so that the various sizes of boxes may be accommodated.

The form 23 has a pivotal connection 24 65 with the upper end of the post 22, and is an-

gularly adjusted by means of a set screw 25 in a lug 26 on the post 22. By means of this screw 25, the form may be given any incline or angular adjustment desired. The carriage 21 is caused to reciprocate by 70 means of a cam 27 integral with or fixed to turn with the gear wheel 10. The cam 27 compels an arm 28 to oscillate, said arm turning freely upon a countershaft 29 in frame 1.

Fig. 20 represents a rocker arm rigidly secured to a transverse shaft 31 supported in frame 1. An arm 32 is pivotally connected to the shaft 31, and is connected by a link 33 with the free end of arm 28, so that the cam 27 75 compels the movement of the pivotal arm 32.

A link 34 connects the arm 32 with a lever 35. This lever 35 is pivotally supported between its ends on a stud 36 projecting laterally from the rocker arm 30 at a point removed from the free end of the latter, and said link 34 is of general compound curvature, so that its ends constitute journals in the arm 32 and lever 35 respectively, and allow these parts to move relative to each 80 other as will be hereinafter explained.

A cam 37 is located on the stud 36 and in the path of movement of the arm 32 limiting the movement of the latter in a rearward direction or to the right in Fig. 4. A set 85 screw 38 in the cam 37 permits the latter to be adjusted on the stud 36, and thereby to vary the stroke of the arm 32.

The upper or free end of the rocker arm 30 is connected by a rod 39 with a depending 90 lug 40 on carriage 21, so that the movement of the rocker arm compels the reciprocation of the carriage. A screw-threaded rod 41 is supported to turn in a bracket 42 on the bottom of carriage 21, and has a crank handle 43 in convenient reach of the operator to permit this rod to be readily turned as desired.

The screw-threaded portion of the rod 41 is positioned in a threaded opening in a lug 100 44 on a yoke 45. The yoke 45 has aligned openings to receive the rod 39 and permit the latter to slide freely therethrough except as controlled by an adjusting sleeve 46 on the rod 39.

The sleeve 46 slides freely on the rod 39 except as limited in its movement by the yoke 45, and is connected by a rod 47 with the upper end of lever 35.

Fig. 48 represents a cam stop on the frame 1 in position to be engaged by the upper end of the lever 35 in one extreme position of the latter, and this cam is adjustably secured by a set-nut 49, so that its position can be varied to control the stroke.

The particular carriage reciprocating mechanism above described is designed to insure a uniform movement of the carriage in one direction, regardless of the size of the box or cover to be operated upon. In 130

other words, the stopping point of the inward movement of the carriage must be precisely the same at all times, so that the paper applied to the box or cover will be forced 5 thereupon in a uniform position.

The operation of this particular mechanism is as follows: The cam 27 forces rod 33 to the right of Fig. 4, causing the pivoted arm 32 to move against the cam 37. At such 10 time, the rocker arm 30 begins to move to the right of Fig. 4, and through the medium of the rod 39, moves the carriage 21 inwardly or to the right in Fig. 4. As soon as the proper position for the carriage is reached, 15 which is the uniform stopping position above referred to, the upper end of lever 35 will engage cam 48, and any further movement of the rod 33 and arm 32 to the right of Fig. 4 will result only in turning the 20 lever 35 on its pivot, which will, through the medium of the rod 47, cause the sleeve 46 to slide on rod 39, hence by adjusting the cam 48, an absolute accurate stopping position can be insured. When the cam 11 compels 25 the parts to move in the opposite direction, rod 33 will swing arm 32 to the left of Fig. 4, moving the lever 35 on its pivot until sleeve 46 engages yoke 45. As the lever can then move no further in this direction, the 30 rocker arm 30 will be caused to move to the left of Fig. 4, and move the carriage 21 to its extreme position toward the forward end of the frame 1.

50 represents a supply roll, from which a 35 continuous strip 51 is drawn over a roller 52 applying adhesive to the under face of the strip 51. The roller 52 is mounted in a reservoir 53 containing adhesive in liquid form, which adhesive may be glue or mucilage, and is maintained in a liquid state by 40 heat or otherwise.

The strip 51 before reaching the roller 52, is passed over a guide 54, and after leaving the roller 52, moves through a scraper 55. 45 This scraper is shown clearly in Fig. 10, where it will be noted that the same consists of a shaft 56 having a wire 57 secured thereto at the ends of the latter, but throughout the greater portion of its length located par- 50 allel with and spaced from the shaft.

The shaft 56 is supported in bearings 58 on the reservoir 53, and at one end is provided with a crank arm 59 carrying an integral yoke 60. The yoke 60 has screw-threaded openings for the reception of the threaded end of a rod 61, and said rod 61 is mounted to turn in a bearing 62 in the upper forward portion of frame 1.

A crank handle 63 is provided on the end 60 of rod 61, so that the rod 61 may be readily turned to adjust the position of the scraper, and exert the desired amount of friction against the surface to remove any surplus- 65 age of adhesive, and compel it to fall back into the reservoir.

It will be noted that by turning the shaft 56, the frictional engagement of the scraper will be varied. The strip of paper 51 is guided by means of a frame 64 rigidly secured to the frame 1, and located above the latter and also by a roller carrying frame 65 secured to a transverse shaft 66 in the forward portion of frame 1. The paper also projects over a transverse box 67, and normally at its free end rests upon needles 68 which project through the box 67 and beyond the same as shown clearly in Fig. 6.

The box 67 is provided at its ends with arms 69, the latter having openings 70 therein to receive bolts 71 depending from the supporting frame 1. The bolts 71 are relatively long, and are provided below the arms 69 with coiled springs 72 which normally hold the box in an elevated position but permit the latter to be forced down- 85 wardly as will be hereinafter pointed out.

The roller carrying frame 65 above referred to consists of two forwardly projecting members 73, and 74 respectively secured to the shaft 66 at their rear ends, and 90 at their forward ends carrying a pressure roller 75 located normally in a plane above the forward ends of the needles 68. This roller 75 is preferably made in sections as indicated, and at its ends is supported in 95 plates 76, the latter having a plurality of openings 77 therein in any of which the trunnions at the ends of the roller may be positioned so as to adjust the roller to suit conditions.

The paper is held upon the top of the box 67 by means of bails 78 pivotally connected at their ends to the members 73 and 74 of the roller carrying frame 65, and these bails give sufficient weight and pressure to hold 105 the paper smooth at all times, and guide blocks 79 are positioned on a transverse rod 80 in frame 1, and serve to hold the paper against lateral movement, said blocks being adjustable on the rod to accommodate different widths of paper.

To operate the roller carrying frame, a cam 81 is secured to shaft 11, and is engaged by a roller 82 on the lower end of an arm 83. This arm 83 has fixed relation to the member 115 73 of the roller frame 65 and may constitute an integral part of the same if desired.

A coiled spring 84 connects the arm 83 with the frame 1, and exerts a rearward 120 pull on the arm, so that when the cam turns to a position to permit it, the spring 84 draws the arm 83 rearwardly and forces the roller 75 downwardly.

The needles 68 above referred to are positioned horizontally, and slide through the box 67, the latter being filled with oil saturated waste 85, so that the needles are kept 125 constantly oiled and an accumulation of mucilage upon the same is prevented.

The rear ends of all of the needles 78 are secured to a cross bar 86, in which the needles are removably held by screws 87, so that they may be removed and replaced 5 if desired. A rearwardly projecting rod 88 is secured to the bar 86, and at its bifurcated rear end is connected to a crank arm 89 on a shaft 90 supported in frame 1.

A short crank arm 91 on shaft 90 is connected by a coiled spring 92 with the stationary frame 64, and tends always to draw the needles in a rearward direction. To limit the turning movement of the shaft 90 by the spring 92, a crank arm 204 is secured 10 to the shaft 90 and is provided with a pin 205 which engages the frame 1, so that the spring is prevented from drawing the needles entirely out of the box. This movement of the needles by the spring is prevented 15 by a member 93 which is pivotally supported midway between its ends on an arm 94 extending rearwardly from the member 73 of the roller frame 65. This member 93 at one end, is provided with a laterally off-set portion 95 having a set screw 96 therein bearing directly upon the arm 94.

The rear end of the member 93 is connected by a rod 98 with the crank arm 91, and the action of spring 92 exerts an upward pressure on the rod 98, such movement being limited by the screw 96 against arm 94. As soon as the cam 81 permits the arm 83 to move rearwardly, and hence permits the spring 84 to draw the roller frame 30 downwardly, the arm 94 is caused to swing in an upward direction. This upward movement of the arm 94 allows the spring 92 to turn shaft 90 in a direction to draw the needles rearwardly from a position under 35 the paper. It will therefore be noted that as the roller begins to descend, the needles begin to move rearwardly out of the way, so that the roller is free to press the paper downwardly upon the box or 40 cover as the case may be which is supported on the form 23. At such time the carriage will be at its extreme inward position, and the roller will press the paper tightly upon the box or cover and hold it 45 in such position as the carriage begins its outward movement. At such time, a pressure pad 99 moves downwardly, and rests upon the paper exerting sufficient pressure thereon as the carriage is moved outwardly 50 or forwardly to insure a proper adhesion. The pressure pad 99 is secured to a vertical bar 100 depending from a U-shaped frame 101. This frame 101 is fixed to a shaft 102, the latter supported to turn in frame 1, and 55 provided on one end with a crank arm 103.

The arm 103 is connected by a link 104 with the shorter member 105 of a bell-crank-lever 106. The longer member 107 of said bell-crank-lever is in the path of 60 movement of a cam 108, the latter secured

to shaft 11, and made in two sections as shown clearly in Fig. 2. These sections of the cam are adjustable relative to each other by means of a set screw 109, so as to regulate the length of the cam surface, and it 70 will be understood that when said cam surface is in engagement with the bell-crank-lever 106, the pressure pad 99 will be maintained in an elevated position and at other times the pressure pad will fall and exert 75 pressure on the box.

To cut the strip of paper 51 into sheets of proper length, we provide a cutting blade 110 secured to a transverse bar 111 fixed to frame 1. This cutter is located sufficiently 80 high to be out of the way of the paper and to press the paper against the same, a swinging frame 112 is provided. This frame 112 is secured to a transverse shaft 113, the latter has a crank arm 114 at one end. The 85 crank arm 114 is connected by a link 115 with a crank arm 116 on the transverse shaft 29.

A crank arm 117 fixed to shaft 29 is engaged at its free end by a cam 118 on shaft 90 11, so that the cam normally holds the frame 112 in its vertical inoperative position. A coiled spring 119 connects the free end of the arm 116 with frame 1, and when permitted by the cam 118 causes the frame 112 95 to swing upwardly, pressing the paper against the cutting blade 110 and severing the same in the proper length, and at the proper time.

A crank arm 120 fixed to crank arm 117 100 is secured by a bolt 121 and a nut 122 with the rear end of rod 123. The forward end of the rod 123 has an eye 124 supported on a transverse rod 125 in frame 1, and is of sufficient flexibility to compensate for the 105 movement necessary.

On the rod 123, an adjustable stop 126 is located, and secured at any position of adjustment by a screw 127. This stop 126 has a beveled end 128 which allows the carriage 21 to move forwardly, but operates to momentarily stop the carriage on its rearward movement while the paper is being cut, so that there will be no drag on the cutter. This stopping of the carriage is but 110 momentary as the stop is moved downwardly by the crank arm 120 as soon as shaft 29 is turned by the action of the cam 118 and spring 119 above described, and there is sufficient flexibility in the reciprocating movement of the carriage to prevent 115 any damage by reason of this stop.

In the manufacture of many styles of boxes, particularly those designed for containing hosiery and the like, it is desirable 120 to secure a tape 129 across the bottom of the box 130, and under the sheet 131 of paper pasted on the bottom of the box as above described.

In Fig. 19 we illustrate a box in its com- 130

pleted form showing the box in an inverted position with the cover 132 underneath, and it is to be understood that our improved machine is designed to place a similar sheet 5 131 on the cover as well as on the bottom of the box. The tape 129 is fed from a spool 133 supported on a journal 134 on frame 1, and is drawn through an eye 135 on a weight guiding frame 136 located at one 10 side of frame 1 as shown clearly in Fig. 1.

The tape 129 is fed across the machine by means of a shuttle 137, the latter guided in its movement by means of parallel rods 138 which are fixed to and supported in a 15 transverse frame 139. The shuttle 137 is in the form of a block with parallel openings 140 to receive the rods 138, and at one end is formed with a chamber 141.

The detail construction of the shuttle and 20 its coöperating parts is shown in Figs. 13 to 16 inclusive. The shuttle 137 is provided with an opening 142 communicating at one side with chamber 141, and in line with a hollow conical guide needle 143.

25 A tape 129 extends through the opening 142 through chamber 141, and through the needle 143, and is held against retrograde movement by a dog 144 held in operative position by a spring 145. A tape holder 146 is provided with openings 147 to receive the rods 138, and is elastically held in a stationary position by means of a rod 148 which is secured to the transverse frame 139.

The holder 146 is provided with a perforated lug 149 to receive the rod 148, and a screw 150 in the lug 149 exerts sufficient pressure on the rod 148 to prevent undue lateral movement of the holder. A coiled spring 151 connects the holder 146 with the 40 free end of rod 148, and acts as a cushion to prevent injury in the event the shuttle strikes the holder with a considerable force. The holder 146 is provided with a chamber 152 having an opening 153 in one side in 45 line with a nozzle 154. The needle 143 of shuttle 137 moves through the opening 153 and the nozzle 154, and deposits the tape 129 in the holder.

A dog 155 in the opening 153 exerts downward pressure on the tape, and holds the latter against movement when the shuttle is withdrawn. This dog 155 is secured upon a shaft 156, and is provided with a spring 157 which exerts sufficient downward pressure on the dog to compel it to do its ordinary functions.

The shaft 156 extends rearwardly from the holder 146, and is supported at its rear end in a bearing 158. A crank arm 159 is 55 secured to shaft 156 and is connected by a link 160 with a crank arm 161. The crank arm 161 is fixed to a shaft 162 which extends through frame 1, and is provided at one side of the frame 1 with a crank arm 163 60 having a roller 164 at its free end in posi-

tion to be engaged by a lever 165, the latter pivotally supported between its ends on the frame 1 as shown at 166, and at its lower free end having a roller 167 held against a cam 168 on shaft 11 by a coiled spring 169. 70

The shuttle 137 is secured at its upper end to a cable 170. One end of this cable is passed over a pulley 171 suspended from a hook 172 at the upper end of vertical weight guiding frame 136, and is secured to 75 a weight 173 which is guided in its vertical movement by parallel rods 174 carried by frame 136, and positioned in openings 175 in the weight. The other end of the cable 170 passes around a pulley 176 supported 80 by a laterally extending arm 177 on frame 1, and is secured to a relatively long crank arm 178 on a transverse shaft 179 supported by frame 1.

A crank arm 180 on shaft 179 is connected by a link 181 with a crank pin 182 on the face of cam 168, so that the crank arm 180 is given a continuous oscillating movement to impart an oscillating movement to arm 178, and to reciprocate the shuttle 137 transversely of the machine. 85

The transverse frame 139 is supported by a pair of crank arms 183. These crank arms 183 are secured to a transverse shaft 185, and one of the arms 183 extends rearwardly 95 beyond the shaft and is provided with a depending link 186 having a bifurcated lower end 187 straddling a pin 188 on a crank arm 189 fixed to shaft 179. A coiled spring 97 connects the rear end of arm 183 with frame 100 1 and normally holds the frame 139 in an elevated position.

By reason of the construction last described, the frame 139 is caused to move downwardly and deposit the tape 129 across 105 the box 130 on the form 23. When the tape is in this lowered position, the shuttle 137 is drawn to the extreme right of Fig. 17 as shown in dotted lines, and the shears 190 are caused to act to sever the tape as will 110 now be described.

The shears 190 consist of a stationary blade 191, and a pivoted blade 192. The stationary blade 191 is secured to a rod 193 mounted to slide in a guide frame 194, its 115 movement being limited by a head 195 on the inner end of the rod. The pivoted blade 192 is provided with a crank arm 196 which is connected by a link 197 with the block 198, and the block 198 is connected by a rod 120 199 with the lever 165. Hence, when the upper end of the lever 165 is moved forwardly, it will first move the rod 193 to position the shears for cutting, and a continued movement of the lever after the rod 125 193 is stopped by the head 195, will cause the pivoted blade 192 to move downwardly and sever the tape.

On the ends of the carriage 21, upwardly projecting perforated lugs 200 are provided, 130

and support L-shaped arms 201. These arms 201 are vertically positioned with their horizontal shorter members secured in the lugs 200 by set screws 202. On the upper 5 ends of the arms 201, relatively wide and flat fingers 203 are located. These fingers 203 engage over the tape as it is positioned on the box, and serve to position the tape at right angles to the longitudinal axis of the 10 box so as to insure a uniformity in the proper positioning of the tape as it is deposited on the box.

It is to be understood that the tape is positioned on the box in advance of the sheet 15 131, so that as the sheet is secured to the bottom of the box by its adhesive, it will at the same time, secure the tape midway the ends of the latter, leaving the ends of the tape free to be tied over the cover of the box as 20 is customary.

On the end of the shaft 8, a balance wheel 206 is preferably located to steady the running of the machine.

To prevent an unnecessary drag of the 25 paper as it is drawn off of the roll 50, a slack creating frame 207 is provided. This frame 207 is of general U-shape with its intermediate portion 208 in position to engage the paper strip 51, and cause the same to 30 unwind slightly from the roll. This frame 207 is provided with a crank arm 209 which is connected by a link 210 with a crank arm 211 on the shaft 31, so that at each oscillating movement of the rocker arm 30, the 35 frame 207 is caused to kick the strip 51 and give sufficient slack in the strip of paper to overcome any unnecessary drag on the strip as it is applied to the box or cover.

The operation of our improved machine 40 is as follows: The operator stands at the forward end of the machine, which is at the left hand end of Figs. 1, 2, 3, 4, and 5, and has in convenient reach, a pile of boxes or covers to receive the sheets 131 thereon. 45 Assuming the operation to be upon the box bottoms, the operator places the box 130 upon the form 23, and then presses the treadle 19 downwardly. This movement of the treadle operates the clutch 4 to start the 50 machine. The carriage 21 moves inwardly, and as soon as it reaches its extreme inward position, the pressure roller 75 moves downwardly to press the end of the paper upon the box. As the pressure roll begins its 55 downward movement, the needles 68 are drawn rearwardly through the box 67 out of the way of the descending roller. After the roller has imparted the initial pressure to the paper, the pressure pad 99 descends, and presses downwardly upon the paper 60 during the forward or outward movement of the carriage 21. During this outward movement of the carriage, the frame 112 is operated to sever the paper against the cutting 65 blade 110, and as soon as the cutting operation

is completed, the needles 68 are projected forwardly and support the end of the paper strip until the roller again descends as above explained. If tape is supplied to the box, it is deposited on the box before the paper, 70 and this positioning of the tape by the shuttle 137, its severance by the shears 190, and its movement downwardly on the box, takes place before the paper is permitted to cover the same. The several cans and co-operating mechanism so times the operation that each step of the process or function of the machine takes place at the pre-determined time, and at each complete reciprocation 75 inwardly and outwardly of the carriage 21, a sheet of paper and the tape are caused to adhere to the bottom of the box. When a top sheet is being applied to the covers of boxes, the tape will not, of course, be used, and in many boxes the tape is not desired, 80 so that this feature of the machine can be operated or not as desired.

In the claims we have used the word "box" to signify any receptacle, either body or cover for receiving the sheet of 90 paper thereupon, and hence in the employment of this term in the claims, we would have it understood that we are not limited thereby.

Various slight changes might be made in 95 the general form and arrangement of parts described without departing from our invention, and hence we do not limit ourselves to the precise details set forth, but consider ourselves at liberty to make such 100 changes and alterations as fairly fall within the spirit and scope of the appended claims.

Having thus described our invention, what we claim as new and desire to secure 105 by Letters Patent is:

1. In a box covering machine, a reciprocating carriage, a box form on the carriage, and means for applying an adhesive covered sheet and a strip of flexible material to the 110 box on the form, said sheet applied to the box during the movement of the form, substantially as described.

2. In a box covering machine, a reciprocating carriage, a box form on the carriage, and means for applying an adhesive covered sheet and a strip of flexible material to the 115 box on the form, said sheet applied to the box during the movement of the form in one direction only, substantially as described.

3. In a box covering machine, a reciprocating carriage, a box form on the carriage, means for applying an adhesive covered sheet and a strip of flexible material to the 120 box on the form, said sheet applied to the box during the movement of the form, and means for adjusting the form relative to the carriage, substantially as described.

4. In a box covering machine, a reciprocating carriage, a box form on the carriage, 125

means for applying an adhesive covered sheet and a strip of flexible material to the box on the form, said sheet applied to the box during the movement of the form in one direction only, and means for adjusting the form relative to the carriage, substantially as described.

5. In a box covering machine, a reciprocating carriage, a box form on the carriage, means for applying an adhesive covered sheet and a strip of flexible material to the box on the form, said sheet applied to the box during the movement of the form, and means for cutting a continuously fed strip 15 into sheets of a size to fit the boxes, substantially as described.

6. In a box covering machine, a reciprocating carriage, a box form on the carriage, means for applying an adhesive covered 20 sheet and a strip of flexible material to the box on the form, said sheet applied to the box during the movement of the form in one direction only, and means for cutting a continuously fed strip into sheets of a size 25 to fit the boxes, substantially as described.

7. In a box covering machine, a reciprocating carriage, a box form on the carriage, means for applying an adhesive covered sheet and a strip of flexible material to the 30 box on the form, said sheet applied to the box during the movement of the form, a pressure roll adapted to be moved against the sheet to press it on the box during a portion of the movement of the carriage in 35 one direction, substantially as described.

8. In a box covering machine, a reciprocating carriage, a box form on the carriage, means for applying an adhesive covered 40 sheet and a strip of flexible material to the box on the form, said sheet applied to the box during the movement of the form in one direction only, a pressure roll adapted to be moved against the sheet to press it on the box during a portion of the movement of the carriage in 45 one direction, substantially as described.

9. In a box covering machine, a reciprocating carriage, a box form on the carriage, means for applying an adhesive covered 50 sheet and a strip of flexible material to the box on the form, said sheet applied to the box during the movement of the form, a pressure roll adapted to be moved against the sheet to press it on the box during a portion of the movement of the carriage in 55 one direction, and a pressure pad engaging the sheet during the completion of said movement, substantially as described.

10. In a box covering machine, a reciprocating carriage, a box form on the carriage, means for applying an adhesive covered 60 sheet and a strip of flexible material to the box on the form, said sheet applied to the box during the movement of the form in one direction only, a pressure roll adapted 65

to be moved against the sheet to press it on the box during a portion of the movement of the carriage in one direction, and a pressure pad engaging the sheet during the completion of said movement, substantially 70 as described.

11. The combination with a frame, of a reciprocating carriage on the frame, means for feeding a continuous strip containing adhesive on one surface, means for severing 75 the strip into sheets and pressing the same upon a box on the carriage, and longitudinally movable needles supporting the free end of said strip, substantially as described.

12. The combination with a frame, of a reciprocating carriage on the frame, means for feeding a continuous strip containing adhesive on one surface, means for severing 80 the strip into sheets and pressing the same upon a box on the carriage, and longitudinally movable needles supporting the free end of said strip, and means for oiling the needles, substantially as described.

13. The combination with a frame, of a reciprocating carriage on the frame, means 85 for feeding a continuous strip containing adhesive on one surface, means for severing the strip into sheets and pressing the same upon a box on the carriage, and longitudinally movable needles supporting the free 90 end of said strip, and a lubricant containing box through which said needles are movable, substantially as described.

14. The combination with a frame, of a reciprocating carriage on the frame, means 100 for feeding a continuous strip containing adhesive on one surface, means for severing the strip into sheets and pressing the same upon a box on the carriage, longitudinally movable needles supporting the free end of 105 said strip, a box containing lubricant saturated waste through which the needles are movable, substantially as described.

15. The combination with a frame, of a reciprocating carriage on the frame, means 110 for feeding a continuous strip containing adhesive on one surface, means for severing the strip into sheets and pressing the same upon a box on the carriage, longitudinally movable needles supporting the free end of 115 said strip, means for withdrawing the needles from beneath the paper when the pressure device is lowered and projecting the needles beneath the strip when the pressure device is elevated, substantially as described.

16. The combination with a frame, of a reciprocating carriage on the frame, means for feeding a continuous strip containing adhesive on one surface, means for severing 125 the strip into sheets and pressing the same upon a box on the carriage, longitudinally movable needles supporting the free end of said strip, means for oiling the needles, means for withdrawing the needles from be- 130

- neath the paper when the pressure device is lowered, and projecting the needles beneath the strip when the pressure device is elevated, substantially as described.
17. The combination with a frame, of a reciprocating carriage on the frame, means for feeding a continuous strip containing adhesive on one surface, means for severing the strip into sheets and pressing the same upon a box on the carriage, longitudinally movable needles supporting the free end of said strip, a lubricant containing box through which said needles are movable, means for withdrawing the needles from beneath the paper when the pressure device is lowered, and projecting the needles beneath the strip when the pressure device is elevated, substantially as described.
18. The combination with a frame, of a reciprocating carriage on the frame, means for feeding a continuous strip containing adhesive on one surface, means for severing the strip into sheets and pressing the same upon a box on the carriage, longitudinally movable needles supporting the free end of said strip, a box containing lubricant saturated waste through which the needles are movable, means for withdrawing the needles from beneath the paper when the pressure device is lowered, and projecting the needles beneath the strip when the pressure device is elevated, substantially as described.
19. In a box covering machine, a reciprocating carriage, a box form on the carriage, means for applying an adhesive covered sheet to the box on the form during the movement of the latter, and means for depositing a strip of flexible material across the box prior to the positioning of the sheet thereupon, substantially as described.
20. In a box covering machine, a reciprocating carriage, a box form on the carriage, means for applying an adhesive covered sheet to the box on the form during the movement of the latter in one direction only, and means for depositing a strip of flexible material across the box prior to the positioning of the sheet thereupon, substantially as described.
21. In a box covering machine, a reciprocating carriage, a box form on the carriage, means for applying an adhesive covered sheet to the box on the form during the movement of the latter, means for adjusting the form relative to the carriage, and means for depositing a strip of flexible material across the box prior to the positioning of the sheet thereupon, substantially as described.
22. In a box covering machine, a reciprocating carriage, a box form on the carriage, means for applying an adhesive covered sheet to the box on the form during the movement of the latter in one direction only, means for adjusting the form relative to
- the carriage, and means for depositing a strip of flexible material across the box prior to the positioning of the sheet thereupon, substantially as described.
23. In a box covering machine, a reciprocating carriage, a box form on the carriage, means for applying an adhesive covered sheet to the box on the form during the movement of the latter, means for cutting a continuously fed strip into sheets of a size to fit the boxes, and means for depositing a strip of flexible material across the box prior to the positioning of the sheet thereupon, substantially as described.
24. In a box covering machine, a reciprocating carriage, a box form on the carriage, means for applying an adhesive covered sheet to the box on the form during the movement of the latter in one direction only, means for cutting a continuously fed strip into sheets of a size to fit the boxes, and means for depositing a strip of flexible material across the box prior to the positioning of the sheet thereupon, substantially as described.
25. In a box covering machine, a reciprocating carriage, a box form on the carriage, means for applying an adhesive covered sheet to the box on the form during the movement of the latter, a pressure roll adapted to be moved against the sheet to press it on the box during a portion of the movement of the carriage in one direction, and means for depositing a strip of flexible material across the box prior to the positioning of the sheet thereupon, substantially as described.
26. In a box covering machine, a reciprocating carriage, a box form on the carriage, means for applying an adhesive covered sheet to the box on the form during the movement of the latter in one direction only, a pressure roll adapted to be moved against the sheet to press it on the box during a portion of the movement of the carriage in one direction, and means for depositing a strip of flexible material across the box prior to the positioning of the sheet thereupon, substantially as described.
27. In a box covering machine, a reciprocating carriage, a box form on the carriage, means for applying an adhesive covered sheet to the box on the form during the movement of the latter, a pressure roll adapted to be moved against the sheet to press it on the box during a portion of the movement of the carriage in one direction, a pressure pad engaging the sheet during the completion of said movement, and means for depositing a strip of flexible material across the box prior to the positioning of the sheet thereupon, substantially as described.
28. In a box covering machine, a reciprocating carriage, a box form on the carriage,

means for applying an adhesive covered sheet to the box on the form during the movement of the latter in one direction only, a pressure roll adapted to be moved against 5 the sheet to press it on the box during a portion of the movement of the carriage in one direction, a pressure pad engaging the sheet during the completion of said movement, and means for depositing a strip of 10 flexible material across the box prior to the positioning of the sheet thereupon, substantially as described.

29. The combination with a frame, of a reciprocating carriage on the frame, means 15 for feeding a continuous strip containing adhesive on one surface, means for severing the strip into sheets and pressing the same upon a box on the carriage, longitudinally movable needles supporting the free end 20 of said strip, and means for depositing a strip of flexible material across the box prior to the positioning of the sheet thereupon, substantially as described.

30. The combination with a frame, of a reciprocating carriage on the frame, means 25 for feeding a continuous strip containing adhesive on one surface, means for severing the strip into sheets and pressing the same upon a box on the carriage, longitudinally movable needles supporting the free end of 30 said strip, means for oiling the needles, and means for depositing a strip of flexible material across the box prior to the positioning of the sheet thereupon, substantially as de- 35 scribed.

31. The combination with a frame, of a reciprocating carriage on the frame, means 40 for feeding a continuous strip containing adhesive on one surface, means for severing the strip into sheets and pressing the same upon a box on the carriage, longitudinally movable needles supporting the free end of 45 said strip, a lubricant containing box through which said needles are movable, and means for depositing a strip of flexible material across the box prior to the positioning of the sheet thereupon, substantially as described.

32. The combination with a frame, of a reciprocating carriage on the frame, means 50 for feeding a continuous strip containing adhesive on one surface, means for severing the strip into sheets and pressing the same upon a box on the carriage, longitudinally 55 movable needles supporting the free end of said strip, a box containing lubricant saturated waste through which the needles are movable, and means for depositing a strip of flexible material across the box prior to 60 the positioning of the sheet thereupon, substantially as described.

33. The combination with a frame, of a reciprocating carriage on the frame, means 65 for feeding a continuous strip containing adhesive on one surface, means for severing

the strip into sheets and pressing the same upon a box on the carriage, longitudinally movable needles supporting the free end of said strip, means for withdrawing the needles from beneath the paper when the 70 pressure device is lowered and projecting the needles beneath the strip when the pressure device is elevated, and means for depositing a strip of flexible material across the box prior to the positioning of the sheet 75 thereupon, substantially as described.

34. The combination with a frame, of a reciprocating carriage on the frame, means for feeding a continuous strip containing adhesive on one surface, means for severing 80 the strip into sheets and pressing the same upon a box on the carriage, longitudinally movable needles supporting the free end of said strip, means for oiling the needles, means for withdrawing the needles from 85 beneath the paper when the pressure device is lowered, and projecting the needles beneath the strip when the pressure device is elevated, and means for depositing a strip of flexible material across the box prior to 90 the positioning of the sheet thereupon, substantially as described.

35. The combination with a frame, of a reciprocating carriage on the frame, means for feeding a continuous strip containing 95 adhesive on one surface, means for severing the strip into sheets and pressing the same upon a box on the carriage, longitudinally movable needles supporting the free end of said strip, a lubricant containing box 100 through which said needles are movable, means for withdrawing the needles from beneath the paper when the pressure device is lowered, and projecting the needles beneath the strip when the pressure device is elevated, and means for depositing a strip of flexible material across the box prior to 105 the positioning of the sheet thereupon, substantially as described.

36. The combination with a frame, of a reciprocating carriage on the frame, means for feeding a continuous strip containing adhesive on one surface, means for severing the strip into sheets and pressing the same upon a box on the carriage, longitudinally 115 movable needles supporting the free end of said strip, a box containing lubricant saturated waste through which the needles are movable, means for withdrawing the needles from beneath the paper when the pressure device is lowered, and projecting the needles beneath the strip when the pressure device is elevated, and means for depositing a strip of flexible material across the box prior to 120 the positioning of the sheet thereupon, substantially as described.

37. The combination with a frame, of a reciprocating carriage on the frame, a box form on the carriage, means for reciprocating the carriage and controlling the move- 130

ment thereof, means for permitting the adjustment of the movement in one direction, said means compelling the uniform stoppage of the carriage on its inward movement, 5 means for depositing a strip of flexible material on a box carried by the carriage, and means for depositing a sheet containing adhesive on the box over the strip during the outward movement of the carriage, substantially as described.

38. The combination with a frame, of a reciprocating carriage on the frame, a box form on the carriage, a paper supply roll, means for supplying adhesive to the paper 15 as it passes from the roll, means for reciprocating the carriage, a kicker operated by said last-mentioned means and constructed to engage the paper strip and cause slack in the same between the roll and the adhesive 20 applying means, and means for cutting a sheet from the strip and applying the same to a box on the form, substantially as described.

39. The combination with a frame, of a reciprocating carriage on the frame, a box 25 form on the carriage, a paper supply roll, means for supplying adhesive to the paper as it passes from the roll, means for reciprocating the carriage, a kicker operated by 30 said last-mentioned means and constructed to engage the paper strip and cause slack in the same between the roll and the adhesive applying means, means for cutting a sheet 35 from the strip and applying the same to a box on the form, a scraper engaging the strip, and means for adjusting the scraper to vary the frictional contact of the same 40 with the strip, substantially as described.

40. The combination with a frame, of a carriage mounted to reciprocate in the frame, a box form on the carriage, a shaft supported by the frame, a rocker arm secured to the shaft, a stud on the rocker arm, 45 a cam on the stud, a lever on the stud, an arm pivoted to the first-mentioned shaft, a link connecting said arm with the lever, the movement of said arm in one direction limited by the cam, means for oscillating the pivoted arm, a rod connecting the free end 50 of the rocker arm with the carriage, a device adjustable on the rod, a sleeve sliding on the rod and limited in its movement in one direction by the said device, a rod connecting said sleeve with one end of said lever, and a device on the frame, engaged 55 by the lever when the rocker arm is moved in one direction, substantially as described.

41. The combination with a frame, a carriage mounted to reciprocate on the frame, 60 a reservoir for adhesive, a roll in the reservoir, means for moving paper over the roll and to the carriage, a scraper pivotally supported on the reservoir, means for adjusting the angle of the scraper, means for positioning a strip of tape across a box on the car-

riage, and means for pressing the paper on the box over the tape, substantially as described.

42. The combination with a frame, of a reciprocating carriage on the frame, means 70 for feeding a strip of adhesive coated paper longitudinally of the frame, a series of horizontal longitudinally movable needles supporting the free end of the strip, means for holding the strip upon the needles, and 75 means for pressing the strip downwardly when the needles are moved longitudinally in one direction, substantially as described.

43. The combination with a frame, of a carriage mounted to reciprocate on the 80 frame, a box form on the carriage, a transverse frame above the carriage, a tape holder at one end of the transverse frame, a shuttle movable on the transverse frame and adapted to position one end of the tape 85 in the holder and hold the tape in a horizontal position over the box form, means for moving the transverse frame downwardly, and means for severing the tape to deposit it on the box, substantially as de- 90 scribed.

44. The combination with a frame, of a carriage mounted to reciprocate on the frame, a box form on the carriage, a transverse frame above the carriage, a tape 95 holder at one end of the transverse frame, a shuttle movable on the transverse frame and adapted to position one end of the tape in the holder and hold the tape in a horizontal position over the box form, means 100 for moving the transverse frame downwardly, means for severing the tape to deposit it on the box, said tape severing means constituting a pair of shears with means for moving the shears longitudinally 105 into position to engage the tape and then operating the shears to sever the tape, substantially as described.

45. The combination with a frame, of a carriage mounted to reciprocate on the 110 frame, a box form on the carriage, a transverse frame above the carriage, a tape holder at one end of the transverse frame, a shuttle movable on the transverse frame and adapted to position one end of the tape 115 in the holder and hold the tape in a horizontal position over the box form, means for moving the transverse frame downwardly, means for severing the tape to deposit it on the box, and devices on the carriage adapted to engage the ends of the tape 120 and hold the same at right angles to the longitudinal axis of the box on the form, substantially as described.

46. The combination with a frame, of a carriage mounted to reciprocate on the frame, a box form on the carriage, a transverse frame above the carriage, a tape holder at one end of the transverse frame, 125 a shuttle movable on the transverse frame 130

- and adapted to position one end of the tape in the holder and hold the tape in a horizontal position over the box form, means for moving the transverse frame downwardly, means for severing the tape to deposit it on the box, said tape severing means constituting a pair of shears with means for moving the shears longitudinally into position to engage the tape and then operating the shears to sever the tape, and devices on the carriage adapted to engage the ends of the tape and hold the same at right angles to the longitudinal axis of the box on the form, substantially as described.
47. The combination with a frame, of a carriage mounted to reciprocate on the frame, a box form on the carriage, a transverse frame above the carriage, a tape holder at one end of the transverse frame, a shuttle movable on the transverse frame and adapted to position one end of the tape in the holder and hold the tape in a horizontal position over the box form, means for moving the transverse frame downwardly, means for severing the tape to deposit it on the box, said shuttle and said holder having openings therein for the reception of the tape, and spring-pressed dogs in the holders holding the tape against movement in one direction, and means for raising the dog of the holder to permit the release of the tape, substantially as described.
48. The combination with a frame, of a carriage mounted to reciprocate on the frame, a box form on the carriage, a transverse frame above the carriage, a tape holder at one end of the transverse frame, a shuttle movable on the transverse frame and adapted to position one end of the tape in the holder and hold the tape in a horizontal position over the box form, means for moving the transverse frame downwardly, means for severing the tape to deposit it on the box, said tape severing means constituting a pair of shears with means for moving the shears longitudinally into position to engage the tape and then operating the shears to sever the tape, devices on the carriage adapted to engage the ends of the tape and hold the same at right angles to the longitudinal axis of the box on the form, said shuttle and said holder having openings therein for the reception of the tape, and spring pressed dogs in the holders holding the tape against movement in one direction, and means for raising the dog of the holder to permit the release of the tape, substantially as described.
49. The combination with a frame, of a carriage mounted to reciprocate on the frame, a box form on the carriage, a transverse frame above the carriage, a tape holder at one end of the transverse frame, a shuttle movable on the transverse frame and adapted to position one end of the tape in the holder and hold the tape in a horizontal position over the box form, means for moving the transverse frame downwardly, means for severing the tape to deposit it on the box, said shuttle and said holder having openings therein for the reception of the tape, and spring-pressed dogs in the holders holding the tape against movement in one direction, and means for raising the dog of the holder to permit the release of the tape, substantially as described.
50. The combination with a frame, of a carriage mounted to reciprocate on the frame, a box form on the carriage, a transverse frame above the carriage, a tape holder at one end of the transverse frame, a shuttle movable on the transverse frame and adapted to position one end of the tape in the holder and hold the tape in a horizontal position over the box form, means for moving the transverse frame downwardly, means for severing the tape to deposit it on the box, devices on the carriage adapted to engage the ends of the tape and hold the same at right angles to the longitudinal axis of the box on the form, said shuttle and said holder having openings therein for the reception of the tape, and spring-pressed dogs in the holders holding the tape against movement in one direction, and means for raising the dog of the holder to permit the release of the tape, substantially as described.

In testimony whereof we have signed our names to this specification in the presence of two subscribing witnesses.
